No. 793,274.

PATENTED JUNE 27, 1905.

O. P. BREITHUT.

RATCHET MECHANISM FOR RECLINING CHAIRS.

APPLICATION FILED NOV. 1, 1904.

UNITED STATES PATENT OFFICE.

OSCAR P. BREITHUT, OF WILLIAMSPORT, PENNSYLVANIA.

RATCHET MECHANISM FOR RECLINING-CHAIRS.

SPECIFICATION forming part of Letters Patent No. 793,274, dated June 27, 1905.

Application filed November 1, 1904. Serial No. 231,007.

To all whom it may concern:

Be it known that I, OSCAR P. BREITHUT, a citizen of the United States, residing at Williamsport, in the county of Lycoming and State 5 of Pennsylvania, have invented certain new and useful Improvements in Ratchet Mechanism for Reclining-Chairs, of which the following is a specification.

Chairs, couches, and like articles of furniture provided with adjustable backs or similar rest are usually equipped with a self-acting ratchet mechanism to hold the adjustable back, rest, or like support in the required adjusted position. Such ratchet mechanism as commonly provided acts on the upward movement 10 of the support to retain it in an adjusted position, but permits said support to have an uninterrupted backward movement, or vice versa.

This invention provides a ratchet mechanism of novel formation which will act in both directions both in the upward and forward or downward and backward movement of the support, whereby a great and varied adjustment of the latter is obtainable and rapid and dangerous movement guarded against.

For a full description of the invention and the merits thereof and also to acquire a knowledge of the details of construction of the means for effecting the result reference is to be had 30 to the following description and accompanying drawings.

While the invention may be adapted to different forms and conditions by changes in the structure and minor details without departing 35 from the spirit or essential features thereof, still some of the preferred embodiments are shown in the accompanying drawings, in which—

Figure 1 is a side view of a reclining-chair 40 embodying the invention, the dotted lines showing an adjusted position of the back and a portion of the housing being broken away to expose the ratchet mechanism. Fig. 2 is a detail view of the ratchet mechanism and adjunctive parts on a larger scale. Fig. 3 is a transverse section on the line $x-x$ of Fig. 2. Fig. 4 is a view similar to Fig. 2 of a modification.

Corresponding and like parts are referred to 50 in the following description and indicated in

all the views of the drawings by the same reference characters.

The invention is shown applied to the back of a reclining-chair, although it is to be understood that it may be used in connection 55 with the head-rest of a couch or similar adjustable support of an article of furniture having a rest adjustable to various angles. The back, rest, or support is indicated at 1, and a brace or connection 2 is connected at one end 60 to the part 1, and its opposite end is constructed to coöperate with a ratchet contrivance. As shown, the free end of the brace or connection 2 is bent laterally, as indicated at 3, and is arranged to coöperate with the teeth 65 or shoulders of the ratchet. For convenience of disposition the ratchet is arranged beneath the arm 4 of the chair and is suitably housed or incased to prevent disarrangement of the parts or anything from coming in contact 70 therewith. The brace or connection 2 operates through a slot or opening formed in the rear end of the housing 5. The ratchet is designated by the reference-numeral 6 and may be of any construction and comprises a series 75 of teeth 7, having their front edges squared and their upper edges rearwardly inclined to admit of the bent end 3 riding upon the teeth as the back or support 1 is moved upward or forward. In the upward or forward adjustment of the back or support 1 the bent or engaging end 3 of the part 2 drops in front of each tooth immediately upon clearing the same, so that upon releasing the support it will be held in the located position. A corresponding series of teeth or shoulders 8 are disposed below the series of teeth 7 and have a rearward arrangement and are adapted to coöperate with the engaging end of the brace 85 2 to retard the backward or downward movement of the support 1 and hold it in an adjusted position. The teeth or shoulders 8 preferably have a rearward and downward inclination, although this is not essential within the purview of the invention. The teeth 8 90 are horizontal and separated by notches 9, which receive the bent or engaging end 3 and in conjunction with the teeth 8 prevent its casual downward displacement. Companion tongues 95 or projections 10 extend over corresponding 100

tongues 8 into the notches 9, leaving a space between opposing parts to provide a free passage for the engaging end 3. The tongues or projections 10 receive and support the part 5 3 when it clears and drops from an upper tongue or projection 8, so as to insure the part 3 engaging the next tooth or shoulder 8 in successive order. The lower rear edge 11 of the ratchet is upwardly and rearwardly inclined, and the upper rear edge 12 is rearwardly and downwardly inclined, the oppositely-inclined edges 11 and 12 intersected to form the point 13. A flat spring 14 is arranged below the inclined edge 11 and is secured at its lower end to the housing or other convenient part of the frame, and its upper end is free and bears against the point 13 and projects a short distance from said point to support the engaging end 3 of the brace when 15 the back or support 1 is at its lowest adjustment. The projecting end of the spring 14 insures engagement of the bent end 3 with the inclined edge 12 of the ratchet, whereby in the upward movement of the back or support 1 the brace or connection 2 will coöperate with the upper series of teeth 7.

The ratchet may consist of a single part or may comprise separate pieces attached to a plate or other support. The construction 30 shown in Fig. 4 is substantially the same as that illustrated in the other views, the only difference being in the formation of the tongues or projections 10, which are pointed or tapered, and in having the teeth or shoulders 8 arranged at a more rapid inclination.

The back or support 1 may be adjusted by direct application of force thereto by grasping the same. However, for convenience a pull rod or bar 15 is connected to the support 40 and extends beneath the arm 14 and is provided with a knob or finger-piece 16. It is to be understood that a ratchet mechanism and pull-rod are provided for each side of the chair or other article of furniture to which 45 the invention may be applied, so as to form a substantial connection.

Having thus described the invention, what is claimed as new is—

1. In combination, an adjustable support, a 50 ratchet having oppositely - arranged sets of teeth, and a connection attached to said sup-

port and coöperating with the oppositely-arranged teeth of the ratchet to positively hold said support in an adjusted position when moved either upward and forward or backward and downward, substantially as set forth. 55

2. In combination, an adjustable support, a connection extended therefrom and having an engaging portion, notches or shoulders arranged to automatically coöperate with the 60 engaging end of said connection to hold the support in an adjusted position when moved backward or downward, said notches or shoulders having forward projections to receive and support said engaging end, and companion 65 projections coöperating with the projections of said shoulders to insure the engaging of the aforesaid connection therewith, substantially as set forth.

3. In combination, an adjustable support, a 70 connection attached thereto and having an engaging portion, a ratchet having upper and lower sets of teeth inversely disposed for co-operation with the engaging end of said connection to hold the support in an adjusted position either upon its forward and upward or backward and rearward movement, and tongues overlapping the respective lower teeth and coöperating therewith, substantially as set forth. 75

4. In combination, an adjustable support, a connection attached thereto and having an engaging portion, a ratchet having upper and lower sets of teeth inversely disposed for co-operation with the engaging end of said connection to hold the support in an adjusted position either upon its forward and upward or backward and rearward movement, tongues overlapping the respective lower teeth and coöperating therewith, said ratchet having the 80 upper and lower edges of its rear portion oppositely inclined to a point, and a flat spring arranged below the lower inclined edge and projected beyond said point, substantially as set forth. 85

In testimony whereof I affix my signature in presence of two witnesses.

OSCAR P. BREITHUT. [L. S.]
